(57) **CLAIM**

The ornamental design for a set of fish-shaped paver and edge pavers as shown and described.

DESCRIPTION

FIG. 1 is an exploded top perspective view of a set of fish-shaped paver and edge pavers showing my new design; FIG. 2 is a top perspective view of the fish-shaped paver shown in FIG. 1;

FIG. 3 is a top plan view thereof; FIG. 4 is a bottom plan view thereof; FIG. 5 is a right side elevational view thereof; FIG. 6 is a left side elevational view thereof; FIG. 7 is a rear elevational view thereof; FIG. 8 is a front elevational view thereof; FIG. 9 is a top plan view of the short edge paver shown in FIG. 1;

FIG. 10 is a bottom plan view thereof; FIG. 11 is a top plan view of the long edge paver shown in FIG. 1; FIG. 12 is a bottom plan view thereof;

FIG. 13 is a front elevational view thereof; FIG. 14 is a rear elevational view thereof; FIG. 15 is a left side elevational view of the short paver; FIG. 16 is a left side elevational view of the long paver; FIG. 17 is a right side elevational view of the short and long pavers;

FIG. 18 is a front elevational view of the short paver; FIG. 19 is a rear elevational view thereof; and, FIG. 20 is a top plan view showing the design in condition of use.

The like pavers shown in broken lines in FIG. 20 represent the environmental subject matters and form no part of the claimed design.
